UNITED STATES PATENT OFFICE.

NATHAN P. BLOOM, OF LOUISVILLE, KENTUCKY.

DESIGN FOR A CABINET FOR A SOUND-REPRODUCING INSTRUMENT OR THE LIKE.

Application filed May 5, 1928. Serial No. 26 577. Term of patent 3½ years.

To all whom it may concern:

Be it known that I, NATHAN P. BLOOM, a citizen of the United States, residing at Louisville, in the county of Jefferson and State of Kentucky, have invented a new, original, and ornamental Design for a Cabinet for a Sound-Reproducing Instrument or the Like, of which the following is a specification, reference being had to the accompanying drawing, forming a part thereof.

The drawing is a perspective view of the cabinet embodying my new design.

I claim:

The ornamental design for a cabinet for a sound reproducing instrument or the like as shown.

NATHAN P. BLOOM.
